A CORPORATION OF MASSACHUSETTS.

SELF-THREADING SHUTTLE.

Application filed November 7, 1927. Serial No. 231,443.

This invention relates to a self-threading shuttle particularly adapted for use with silk weft or other fine weft having similar characteristics.

- 5 It is the principal object of our invention to provide an improved threading mechanism for such a shuttle, designed to readily receive and retain the thread and to provide a yielding tension or slack take-up therefor.
- 10 With this general object in view, a feature of our invention in its preferred form relates to the provision of two swinging members cooperating to yieldingly tension the filling yarn or weft and to take up the slack thereof.
- 15 Our invention further relates to arrangements and combinations of parts which will be hereinafter described and more particularly pointed out in the appended claims.

A preferred form of the invention is shown 20 in the drawings in which

Fig. 1 is a plan view of a shuttle embodying our improvements;

Fig. 2 is a partial sectional plan view, taken through the threading end of the shuttle;

25 Fig. 3 is a view similar to Fig. 2 but showing the parts in different position;

Fig. 4 is a partial sectional side elevation, looking in the direction of the arrow 4 in Fig. 2; and

30 Figs. 5, 6 and 7 are sectional end elevations, taken along the lines 5—5, 6—6 and 7—7 of Fig. 2 respectively.

Referring to the drawings, we have shown 35 a shuttle S having a bobbin B mounted there-in and preferably having friction material 10 secured along one side of the shuttle and lightly engaging the weft W on the bobbin.

At the front end of the shuttle, a recess or 40 thread passage 12 is formed extending downward from the upper side of the shuttle and extending longitudinally forward along the axis of the shuttle.

At its front end, the passage 12 is provided with an offset portion 13 forming a 45 lateral outlet for the thread and having pins 14 mounted vertically therein and providing a guideway or eye for the shuttle.

A swinging arm 20 is pivoted at 21 in a 50 slot 22 formed in the rear side wall of the shuttle, and a rearward projection 23 of the arm 20 has an elastic member 24, preferably of rubber cord, connected thereto for yieldingly tensioning said arm. The arm 20 extends transversely into the passage 12 and

has an offset portion 25 extending forward 55 along the passage 12. At its front end, the arm 20 is provided with a hook-shaped end portion 27, and said arm is preferably arched as indicated at 28 (Fig. 4) adjacent the end portion 27. 60

A second tension member 30 is pivoted at 31 in the passage 12 and is provided with a hook-shaped thread-engaging end portion 32 (Figs. 2 and 4). A rearward extension of the arm 30 is received in a slot 33 (Fig. 6) in the 65 lower face of a guide member 35, mounted on the portion 25 of the tension arm 20.

The guide member 35 thus forms a connection between the two tension arms, effective to cause the thread-engaging portions of the 70 two arms to move simultaneously in opposite directions. The upper portion of the guide 35 is shaped to assist in guiding the weft W to threading position.

A metal casting or support 40 is preferably mounted in the passage 12, providing a support for the pivot 31 of the tension member 30, also providing thread guiding portions 41 and 42 (Fig. 7), and having a depending portion 43 supporting one of the 75 thread guiding members 14. The support 40 also has a rear guide portion or plate 47 (Fig. 5) to receive the thread W as it enters the threading mechanism.

Having described the details of construction of our improved threading mechanism, 80 the operation thereof is as follows:

When a fresh shuttle is inserted and the thread W is drawn forward through the shuttle eye by the first flight of the shuttle, the 85 thread passes downward around the plate 47 (Fig. 5) and guide member 35 (Fig. 6) and enters the hook-shaped end 27 of the portion 25 of the tension arm 20, as shown in Figs. 2 and 4. As the shuttle makes its return flight, 90 the thread is drawn into the lateral passage 13 between the guide pins 14, and the tension of the thread swings the arm 20 to the position shown in Fig. 3, but with the thread 95 stretched across the arch 28.

At the same time, the hook-shaped end 32 of the second arm 30 moves rearward under the arch 28 and engages the thread where it is stretched across the arch, causing the thread to be caught under the hooked end 32 100 of the arm 30. The thread thus assumes the position indicated in Fig. 3.

When the tension is relieved, the thread-

engaging ends of the arms 20 and 30 will be separated, assuming the normal position shown in Fig. 1, but whenever the tension is increased the parts will return to the position 5 shown in Fig. 3.

The device thus yieldingly tensions the weft at all times and is adapted to immediately take up slack weft and to prevent snarling or kinking of the filling when slackness occurs.

10 The device is exceedingly simple, having only two moving parts and has been found extremely well adapted for the purpose for which it is designed.

Having thus described our invention and 15 the advantages thereof, we do not wish to be limited to the details herein disclosed, otherwise than as set forth in the claims, but what we claim is:—

1. A self-threading shuttle having an open 20 thread passage, a tension arm mounted to swing transversely of the shuttle in said passage, a second movable tension arm, said arms being operatively connected to effect simultaneous thread-tensioning movements in opposite directions, and means to provide tension 25 for said arms.

2. A self-threading shuttle having an open 30 thread passage, a tension arm mounted to swing transversely of the shuttle in said passage, a second movable tension arm, and means to tension said first arm, said first arm being connected to actuate said second arm and to thereby move the thread-engaging portions of said two arms simultaneously in 35 opposite directions.

3. A self-threading shuttle having an open 40 thread passage, a tension arm mounted to swing transversely of the shuttle in said passage, a second movable tension arm, yielding means to move said arms, said arms having hook-shaped weft-engaging portions engaging the thread on opposite sides thereof, said

arms being connected to move simultaneously in predetermined relation and in opposite directions.

4. A self-threading shuttle having an open 45 thread passage, a tension arm mounted to swing transversely of the shuttle in said passage, a second movable tension arm, and yielding means to move said first arm, said first arm having a thread guiding member mounted thereon and operatively engaging said second arm to move the thread-engaging portions of said arms simultaneously in opposite directions.

5. A self-threading shuttle having an open 50 thread passage, a tension arm mounted to swing transversely of the shuttle in said passage, a second movable tension arm, and yielding means to move said arms, said first arm 55 having a thread-engaging end portion and having an upwardly arched portion adjacent thereto, and said second arm having a hook-shaped end movable under said arched portion to engage the weft adjacent said thread-engaging end portion.

6. A self-threading shuttle having an open 60 thread passage, a tension arm mounted to swing transversely of the shuttle in said passage, a second movable tension arm, and yielding means to move said arms, said first arm 65 having a thread engaging end portion and having an upwardly arched portion adjacent thereto, and said second arm having a hook-shaped end movable under said arched portion to engage the weft adjacent said thread-engaging end portion, and said hook-shaped end extending below the plane of movement of said first tension arm to prevent unthreading of the shuttle.

In testimony whereof we have hereunto affixed our signatures.

JESSE R. SHUTT.

ALBERT A. GORDON.
